INVENTOR,

William A. Robinson,

By Wilmot D. Thurston, ATTY.

UNITED STATES PATENT OFFICE.

WILLIAM A. ROBINSON, OF WOONSOCKET, RHODE ISLAND, ASSIGNOR TO MANVILLE COMPANY, OF PROVIDENCE, RHODE ISLAND, A CORPORATION OF NEW JERSEY.

TEXTILE ARTICLE PROVIDED WITH LAPPET FIGURES AND THE METHOD OF PRODUCING THE SAME.

No. 820,602.

Specification of Letters Patent.

Patented May 15, 1906.

Application filed May 9, 1904. Serial No. 206,999.

To all whom it may concern:

Be it known that I, WILLIAM A. ROBINSON, of Woonsocket, in the county of Providence and State of Rhode Island, have invented 5 certain new and useful Improvements in Textile Articles Provided with Lappet Figures and the Method of Producing the Same; and I do hereby declare the following specification, taken in connection with the accompanying drawings, forming a part of the same, to be a full, clear, and exact description thereof.

Heretofore textile fabrics provided with lappet patterns or designs have customarily 15 been woven in continuous lengths with no line of demarcation between successive articles to be made from the fabric, any desired length of the fabric suitable for the article to be made—such, for instance, as a window-curtain—being cut off from the fabric. Furthermore, whenever separate or discontinuous lappet patterns or designs were employed such patterns or designs were comparatively small and of such character that 20 they would necessarily be repeated a number of times in a length of the fabric suitable for the formation of any article of commerce—such, for instance, as a handkerchief or a bureau-cover.

30 The present invention consists in weaving a series of articles—such as handkerchiefs, for instance—in a continuous fabric with demarcations between the successive articles, indicating where they are to be separated from each other, each of said articles when thus 35 separated being provided with a single unitary lappet pattern or design.

A further feature of invention consists in producing each of said articles in the continuous 40 fabric by a single repeat of the pattern mechanism, the unitary lappet pattern or design being likewise produced by such single repeat and so that each repeat for the lappet pattern likewise produces a complete article provided with such single unitary lappet pattern or design pertaining to and characterizing the article as an entirety. In some cases, as in producing such a unitary lappet pattern or design in the form of a border, for instance, it may be desirable to form 45 a portion of the lappet pattern by one pat-

tern mechanism and to form another portion of the lappet pattern by another pattern mechanism.

A further feature of invention therefore 55 consists in producing an article having a unitary lappet pattern or design produced at a single repeat, one portion of such unitary lappet pattern being produced by one pattern mechanism and another portion of such unitary lappet pattern being produced by another pattern mechanism, the two portions of the lappet pattern thus formed being 60 matched together to form the complete unitary lappet pattern or design characterizing 65 the article to which it pertains.

The unitary lappet pattern or design referred to need not be a continuous lappet figure, but may be, and usually would be, composed of a series of separate lappet figures, and in the drawings, hereinafter to be referred to, the unitary lappet design, consisting in this case of a border, is shown as composed of a series of separate lappet figures in the form of spots.

75 Referring to the drawings, Figure 1 represents two articles—as, for example, two handkerchiefs—woven successively in a continuous fabric, each of said articles embodying a lappet pattern or design in the form of a border composed of individual lappet figures in the form of spots. Figs. 2 and 3 are developments, on a large scale, of two pattern-surfaces to be employed in the production of 80 one of the articles shown in Fig. 1.

85 In the drawings, A A represent two handkerchiefs or other articles woven successively in a continuous fabric, a portion of which fabric only is shown. The dotted line x x indicates the point where the two articles are 90 to be separated from each other. In the drawings each article extends the entire width of the fabric and is square in shape. Assuming the fabric shown in the drawings to be, say, fourteen inches wide and the 95 handkerchief or article thus to be fourteen inches square, it is evident that, if desired, a fabric of twice this width, or twenty-eight inches wide, may be woven, in which case two articles fourteen inches square may be 100 woven side by side in the fabric and subsequently separated from each other length-

wise of the fabric, as well as crosswise thereof. So also, if desired, articles—as, for example, bureau-covers—may be woven with each article extending the width of the twenty-
5 eight-inch fabric, thereby forming articles which when separated from each other would be rectangular in shape instead of square, each separate article being thus twenty-eight inches long and fourteen inches wide.

10 In the embodiment of the invention shown in the drawings, in which the unitary lappet pattern or design for the article consists of a border composed of individual lappet figures in the form of spots, a portion of said unitary lappet design or border is produced by one pattern-surface and the other portion of said unitary lappet design or border is produced by another pattern-surface. In other words, the side portions of the border or design comprising
15 the eleven lappet figures or spots *a* on each side are produced under the control of one pattern-surface—such, for instance, as that represented at Fig. 2—while the cross portions of said border or design comprising
20 the nine lappet figures or spots *b* on opposite sides are produced under the control of another pattern-surface—such, for instance, as that represented at Fig. 3. These two portions of the border or design are matched together, thereby forming the complete border and the complete unitary lappet pattern or design for the handkerchief. It will also be seen that with pattern-surfaces like those shown in Figs. 2 and 3 this entire unitary lappet pattern or design and also the entire article itself are produced by a single repeat of the pattern-surfaces and, on the other hand, that each repeat of the pattern-surfaces produces a complete article provided with a unitary
25 symmetrical lappet pattern or design pertaining to and characteristic of the article as an entirety. It will be further noted that the production of a unitary lappet pattern or design for each article furnishes a guide for the
30 separation of the articles when woven successively in a continuous fabric, the line of division being at a point midway between the termination of one design and the beginning of the next succeeding design.

35 40 45 50 55 55 As will be understood, the invention may be employed in the production of any article which it is desired to provide with a lappet pattern or design, and in the foregoing specification handkerchiefs and bureau-covers are referred to only as illustrations of articles to which the invention is applicable.

What I claim as my invention, and desire to secure by Letters Patent, is—

1. The method of producing articles provided with lappet patterns or designs, which consists in weaving successive articles in a continuous fabric, and providing, each article with a unitary lappet pattern or design

pertaining to said article, substantially as described.

65

2. The method of producing articles provided with lappet patterns or designs which consists in weaving successive articles in a continuous fabric, and providing each article with a unitary lappet pattern or design, said lappet pattern and the article to which it pertains being produced by a single repeat, substantially as described.

70

3. The method of producing articles provided with lappet patterns or designs which consists in weaving successive articles in a continuous fabric, and providing each article with a unitary lappet pattern or design, a portion of which is produced by one pattern-surface, and another portion of which is produced by a second pattern-surface, the two portions being matched together to form the complete unitary design, substantially as described.

75

4. The method of producing articles provided with lappet patterns or designs, which consists in weaving successive articles in a continuous fabric, and providing each article with a unitary lappet pattern or design, the two succeeding lappet designs serving as guides for the separation of the articles, substantially as described.

80

5. An article, such as a handkerchief or the like, provided with a unitary lappet pattern or design, substantially as described.

85

6. An article, such as a handkerchief or the like, provided with a unitary lappet pattern or design composed of individual lappet figures, substantially as described.

90

7. An article, such as a handkerchief or the like, provided with a unitary lappet pattern or design composed of individual lappet figures symmetrically arranged, substantially as described.

95

8. An article, such as a handkerchief or the like, provided with a unitary lappet pattern or design produced at one repeat, substantially as described.

100

9. An article, such as a handkerchief or the like, provided with a unitary lappet pattern or design, said lappet pattern and the article to which it pertains being produced at one repeat, substantially as described.

110

10. An article, such as a handkerchief or the like, provided with a unitary lappet pattern or design, a portion of which is produced by one pattern-surface, and another portion of which is produced by a second pattern-surface, the two portions being matched together to form the complete unitary design, substantially as described.
